SAMUEL H. DAVIS AND DAVID W. DAVIS, OF DETROIT, MICHIGAN.

Letters Patent No. 98,852, dated January 18, 1870.

IMPROVED ICE-CRUSHING TABLE.

The Schedule referred to in these Letters Patent and making part of the same.

To whom it may concern:

Be it known that we, SAMUEL H. DAVIS and DAVID W. DAVIS, of Detroit, in the county of Wayne, and State of Michigan, have invented a new and useful Improvement in Ice-Crushing Table; and we do declare that the following is a true and accurate description thereof, reference being had to the accompanying drawings, and to the letters of reference marked thereon, and being a part of this specification.

The nature of this invention relates to a device for crushing ice into pieces of a small and nearly uniform size, suitable for freezing ice-cream, and other articles, and for packing oysters, fish, and other articles that require to be kept at a low temperature.

The invention consists of a strong frame, supported upon suitable legs, and provided with lateral metal bars, and suitable side and end-boards, as more fully hereinafter described.

In the accompanying drawings—

A represents a strong frame, made of any suitable material, and mounted upon suitable supports B.

Bars of iron or steel C, or of any appropriate material, are imposed laterally across the frame, one-half inch or more apart, according to circumstances.

These bars may be of any desired form and material, preferably, however, of steel, and of diamond-form, and so laid upon the frame that they will be sharp on top and tapering underneath, as then the ice

will not clog in its passage, as it will be apt to do when they are square or rectangular.

The bars should be so secured that they can readily be taken out separately, to be ground or filed.

The ice to be broken should be placed upon the bars in cakes, say, varying in weight from twenty-five to two hundred pounds, the side and end-boards D, when in place, preventing it from sliding off.

A smart blow with a small axe, or other suitable device, will break the ice and drive it through the grating, thus making it into nearly uniform-sized pieces, for the purpose set forth.

The side-boards D may be secured rigidly to the frame-work A, or in such a manner that they can be easily removed.

With this device one man can crush more ice in one hour than four men can do in the same time with the most improved ice-mills, while the apparatus is cheap and durable, and the process simple and easy.

What we claim as our improvement in an "ice-crushing table," is—

The arrangement of the bars C with their sharp angular edges, and the two outside bars E with upper flat surfaces, and side and end-pieces D, in hopper-form, on leg B, as shown and described.

S. H. DAVIS.
